APPARATUS FOR UNLOCKING ORE BODIES TO EXTRACT SULPHUR AND IRON THEREFROM

Harry Comer Wolf, Irvine, Ky.

Application September 14, 1938, Serial No. 229,806

1 Claim. (Cl. 266—19)

My invention relates to an apparatus which I have employed for the unlocking of ore bodies to extract sulphur or iron or other metallic values therefrom, in practicing the process described in my United States Letters Patent No. 2,103,131.

In the operation of unlocking ore bodies as described in my Patent No. 2,103,131, I have found it necessary to pulverize the ore which is to be processed by my method; in practice I find most ores require pulverization to the point of 200 mesh.

In the processing of this pulverized ore, I have found in practice that it is necessary that the ore be processed in a retort that is sufficiently and properly sealed to permit absolute control of the atmosphere in the retort, particularly to the exclusion of all outside free air.

When gases are introduced into the retort in connection with my process, I have found that the apparatus must be so constructed that the desired gas which is introduced and no other outside gas or air can be admitted to the retort.

In practice I have found I can employ a wide variety of retorts and retorting apparatus adaptable to my process, which I equip with means to seal the retort so as to control atmosphere in the retort. I also provide a means of agitation inside of the retort. This means of agitation may be rabbles, fins, rotation, interrupted rotation, drag line, charge and discharge conveyors, gas pressure, or any other means of agitation in the retort.

In the operation of my process described in my method patent above mentioned, I have found it is possible, so long as the above conditions are complied with, to operate either as a continuous or as a batch process, and accordingly, either continuous or batch apparatus may be suitable according to the local conditions where the process is employed.

In the operation of my process, I find that a normal discharge of the desulphurized ore from the retort results frequently in the contamination of the sulphur, sulphur vapors, or sulphur gases, with the finely comminuted ore, which is frequently carried by the velocity of the sulphur bodies along to the receiving chambers. I have overcome this difficulty by utilizing a two-way takeoff, having upwardly and downwardly directed discharge portions, located at the discharge end of the retort, which permits the ore to drop downwardly from the retort thermally controlled while the vaporized sulphur passes upwardly through the upward discharge portion. This upward passage should be equipped with various types of

dampers by means of which the area may be increased or decreased at will, to control the velocity of the vaporized sulphur, or vapor or gas which comes from the retort as a result of the processing.

In the operation of my process as above referred to, I have found that the sulphur produced is in the form of very finely divided particles and in the point of recovery as solid sulphur, it is necessary that the condensation and precipitation occur with instantaneity. I have also found a wide variety of condenser and precipitator systems and condenser and precipitator methods suitable for this purpose, providing they will condense or precipitate with an instant reaction.

As to separations in the operation of my process, I have found it desirable to concentrate and dress the ore if the values recovered are not uniformly contained in all of the ore being processed. Any suitable apparatus for this purpose is satisfactory, and jig tables, flotation, or any type of separations equipment is suitable.

I have found in practical operation of my method, that the desulphurized ore which drops from the retort downwardly through the two-way takeoff, is not sintered but is still in a pulverized form, and the iron or other metallic values in this desulphurized ore may be recovered by any of the well known methods and apparatus. If silica is present in this discharged ore, the iron in whatever form it may occur, may be separated from the silica by magnetic separation, or by dry or wet flotation, or any of the well known separations methods; or the mass, while still hot, may be dropped into electric or other types of furnaces where the silica and other impurities may be slagged off. Obviously, if other metallic values than iron are desirable, before slagging, the desulphurized ore must be passed through any of the well known methods for recovery of whatever particular mineral or metal other than iron, is desired to be recovered.

The principal object of my invention is to provide apparatus which can be employed for the recovery of sulphur and iron from pyrites.

A further object is to provide in an apparatus of the class described, a two-way takeoff at the discharge end of the retort, said takeoff having an upwardly extending discharge for the passage of the sulphur vapor and a downwardly depending discharge for the ore.

A further object is to provide means whereby the area of either the upward or downward takeoff, or both of them, may be varied to suit the conditions under which the plant is operating.

A further object is to provide means for condensing the sulphur vapor instantly after it leaves the takeoff.

A further object is to provide means to separate the iron from the desulphurized ore.

A further object is to provide means to introduce an inert gas into the interior of the retort.

A further object is to provide means to control and exclude all outside free air from the retort.

A further object is to provide means to agitate the mass in the retort.

My means of accomplishing the foregoing objects may be more fully comprehended by having reference to the accompanying drawing, which is hereunto annexed and is a part of this specification, in which the figure is a diagrammatic view of the complete apparatus.

This view is made in that form for the reasons set forth above; namely, that the precise form of the different means employed, I do not regard as important provided the various parts are equipped with means to obtain the desired results.

As shown in the drawing, I provide means for crushing the ore as illustrated it comprises a jaw crusher 1, a gyratory crusher 2, a ball mill 3. After the ore has passed through these crushers, it is preferably passed through an air separator 4 and a floatation cell 5 into a storage bin 6. This bin is preferably provided with an inwardly tapering portion 7 which terminates in a chute 30 which delivers material to a hopper 8 through which the ore is conveyed to the retort 9. Inside of the retort 9 I mount a plurality of agitators 10 as the ore must be continuously agitated during the vaporizing of the sulphur. As hereinbefore stated, no specific form of agitator is requisite providing it is capable of constantly agitating the ore body inside of the retort 9. Means for introducing an inert gas into the retort consists of a tank 11, which is adapted to contain the gas, and a pump 12, as shown, it is of the rotary type. The discharge side of the pump is connected to the interior of the retort 9 by suitable pipe connections 12a.

At the discharge end of the retort 9 I mount my improved takeoff which is provided with an upwardly extending portion 13 and a downwardly depending portion 14. The portion 13 is connected to a condenser 15 which may be cooled by the circulation of water through coils 16 and 17. The coils are connected to water inlet and outlet pipes 18 and 19. The pipe 18 leading from a suitable source of water supply (not shown). Under some circumstances it may be found desirable to connect the condenser 15 to a pump 20 to assist in drawing the sulphur vapor through the takeoff and into the condenser 15.

The upward discharge 13 of the takeoff is provided with one or more dampers or restrictors 21, which are controllable as to position, such control permitting increase or decrease of

the upward orifice for the purpose of control of the velocity of vapors or gases passing upward from the retort to the condenser, and also for the purpose of providing baffles against which certain portions of the finely divided ore may impinge, thereby retarding the flow of finely divided ore carried upward by the vapor or gas stream.

The downwardly depending portion 14, through which the ore passes to a separator, is provided with one or more dampers or restrictors 22, which restrictors are adjustable to provide a cross section of the downward path in proportion to the quantity of ore that is flowing, thereby aiding in the exclusion of air from the takeoff. As illustrated, I show an electromelt arc furnace 23, as a separator, though it is obvious any suitable type may be employed.

In some cases I find it desirable to provide a screw conveyor 24 to carry the sulphur from the condenser 15. If desired it may be arranged to deliver the sulphur (not shown) to a belt conveyor 25.

The operation of my device is as follows: The pyrites are delivered to the crushers where it is reduced to 200 mesh before it is delivered to the storage bin 6. From this bin, it drops by gravity through a seal 26 and chute 30 to the retort 9, in which it is heated out of contact with the atmosphere and in any suitable manner (not shown) while it is being constantly and continuously agitated by the motion of the agitators 10. When the sulphur is vaporized it passes through the upwardly extending portion 13 of the two-way takeoff into the condenser 15 where it is instantly cooled and the solid sulphur is deposited in the bottom of the condenser 15, from which point it is removed by the conveyor 24 and delivered to the desired destination. The desulphurized ore drops down through the portion 14 of the two-way takeoff into a suitable separator 23.

Having described my invention, what I regard as new and desire to secure by Letters Patent is:

In an apparatus for unlocking ore bodies to extract sulphur and iron therefrom, a retort normally closed to atmosphere, means for introducing ore and inert gas into said retort near one end thereof, means for agitating ore in said retort, said retort having a delivery end connected to a take-off, said take-off having an upwardly directed substantially vertical branch for conducting sulphur vapor to a condenser and a downwardly directed substantially vertical branch for discharging desulphurized ore, and adjustable restricting means imposed in both of said branches constituting baffles arranged one above the other serving to restrict the effective area of said branches, the restricting means in said upwardly directed branch also serving to separate any solids from said vapors by impact.

HARRY COMER WOLF.
